UNITED STATES PATENT OFFICE.

PAUL O. E. FRIEDRICH, OF NEW YORK, N. Y., AND JOHN G. LYMAN, OF PHILADELPHIA, PENNSYLVANIA, ASSIGNEES, BY DIRECT AND MESNE ASSIGNMENTS, TO CALORIS MANUFACTURING COMPANY, A CORPORATION OF DELAWARE.

VACUUM-BOTTLE.

No. 902,528.

Specification of Letters Patent.

Patented Oct. 27, 1908.

Application filed March 5, 1908. Serial No. 419,411.

To all whom it may concern:

Be it known that we, PAUL O. E. FRIEDRICH, a citizen of the United States, residing in the city, county, and State of New York, and JOHN G. LYMAN, a citizen of the United States, residing in the city and county of Philadelphia, State of Pennsylvania, have invented a new and useful Vacuum-Bottle, of which the following is a specification.

10. Our invention consists of a new and useful heat and cold non-conducting bottle or receptacle and consists in providing an insulation, of heat and cold non-conducting material, between the glass and the metal covering thereof.

It further consists in providing an additional covering for the glass.

It further consists of other novel details of construction, all as will be hereinafter 20 fully set forth.

Figure 1 represents a vertical sectional view of a heat and cold non-conducting bottle or receptacle embodying our invention. Fig. 2 represents an enlarged sectional view 25 of a portion of the bottle.

We have found in practice that owing to the uses to which receptacles of this character are subjected that the glass bottles are easily broken and in addition, that it is advantageous to provide all the heat and cold non-conducting material possible. In the drawing we have shown a construction for overcoming these defects and for carrying out our invention but it will be evident that the arrangements of the parts may be varied and other instrumentalities may be employed which will come within the scope of our invention and we do not, therefore, desire to be limited to the exact construction herein 35 shown and described but desire to make such changes as may be necessary.

1 and 2 designate the two glass bottles between which is provided the space 3, the air from which is suitably exhausted forming a 40 vacuum, said bottles being secured together in any suitable or desired manner and being provided with the usual coating of suitable silver 4 and 5, the former on the outer wall of the inner bottle and the latter on the 45 inner wall of the outer bottle.

6 designates the outer covering for the bottles preferably of metal and between which and the bottles we provide the filling or cushion 7 of some suitable heat and cold

non-conducting material, such as natural 55 wool. In this way we provide a cushion for the bottles which prevents breakage of the same and which at the same time assists as a non-conductor for heat and cold. In addition, we may provide if necessary, an insulating covering 8 to the outer glass bottle such as oxalic acid, preferably subjecting the bottles to a bath thereof, before placing the same in the metal casing 6.

The acid will serve to assist as a non-conductor for heat and cold. If desirable, we may provide a coating as 9 for the acid consisting preferably of paraffin, which prevents injury to the acid and will further assist as a non-conductor to heat and cold.

From the above it will be seen that we provide a receptacle which is formed of separate receptacles having a vacuum therebetween and heat and non-insulating material applied to the outer wall of the outer receptacle, or place insulating material between the receptacles and the metal casing, which surrounds the receptacles, the latter material serving also as a cushion between the receptacle and the metal casing.

Having thus described our invention, what we claim as new and desire to secure by Letters Patent, is:—

1. In a device of the character described, inner and outer vessels having a vacuum 85 therebetween, a coat of oxalic acid on the exterior of the vessels and a casing for said vessels.

2. In a device of the character described, inner and outer vessels having a vacuum 90 therebetween, a coat of paraffin upon the outer vessel and a casing for said vessels.

3. In a device of the character described, inner and outer vessels having a vacuum 95 therebetween, oxalic acid on the outer vessel, paraffin exterior to said oxalic acid and a casing for said vessels.

4. In a device of the character described, inner and outer vessels having a vacuum therebetween, oxalic acid on the exterior of 100 the outer vessel, paraffin surrounding said acid, a metallic casing for said vessels and a cushion between said paraffin and said casing.

PAUL O. E. FRIEDRICH.
JOHN G. LYMAN.
